ABSTRACT OF THE DISCLOSURE

A tuning device for a stringed musical instrument with which a selected one of the strings of the instrument can be gradually and accurately tuned by continually biasing a spindle into rotation transmitting play-free engagement with a worm wheel which, in turn, is secured to a rotary shaft having secured thereto the string to be tuned.

The present invention relates to a device for the tuning of string instruments (a so-called "mechanics") comprising a worm gear which has been located on a plate its wheel being supported on a shaft serving for winding up the string and its spindle one end of which has been provided with a turning handle being supported on either side of its threaded portion.

With devices of the present type rapid, free from play engagement of spindle and wheel will be required in order to ensure quick, secure and accurate tuning of the string's pitch.

In the devices already known spindle and wheel of the worm gear are located on a plate which will be screwed onto the string instrument, while the bearing shaft of the wheel is located in a bore of the plate and the spindle is supported by two brackets fixed to the plate. In this connection it is already known to provide the plate in such a manner that it is at the same time bearing the spindle. For this purpose, for instance, on either side of the plate vertical projections with bores to receive the spindle have been provided, or the spindle bearings together with the plate have been produced from one piece, for instance, by spray or pressure casting.

In these devices already known the distance between spindle and wheel axles is always the same. Consequently, free from play engagement between spindle and wheel will not be guaranteed unless the individual components of the device will have been produced and assembled observing utmost precision in which case observation of the appropriate axle distance will be most decisive. However, in the production of these devices application of maximum accuracy is undesirable with respect to costs, resulting in the fact widely known, i.e. that the devices on the market are subject to considerable play. If the distance between spindle and wheel axles is smaller than the theoretical tooth ing value, the worm gear will be subject to obstruction. If the distance between axles is greater than said theoretical tooth ing value, there will be play between the tooth profile of spindle and wheel.

If, for instance, the string is tuned to a higher pitch, the tooth profile of the spindle will contact without any play the tooth profile of the wheel which is submitted to the tensional force of the string. If, however, the string is subsequently tuned to a lower pitch, i.e. if the spindle is turned into the opposite direction, the wheel is not easily following the spindle movement, but it is following the same more or less with jerks until the existing play will have been overcome and free from play engagement between spindle and wheel restored. Precise tuning of the string will usually be effected by repeated higher and lower tuning around the desired tone until the player of

2

the string instrument will gradually have arrived at said desired tone. But especially in this case such play will be extremely annoying. For in extreme cases, i.e. if the desired tone is exactly located in the gap defined by the play between wheel and worm, precise tuning will not be possible at all.

Such unfavorable effect as described does, however, not only occur in the presence of excess distance between axles. Any play between spindle and wheel profiles resulting from inaccurate tooth ing as well as any play in the spindle or wheel bearings will have the same unfavorable effect. It may even happen that play occurs in a gear which has initially been free from play after prolonged utilisation of the string instrument due to wear.

Play will be especially great in those cases where several individual plays are acting in the same direction. On the other hand, it may also happen of course that several individual plays acting in opposite directions may partly or completely neutralise their total effect thus simulating more or less play free engagement of spindle and wheel.

The object of the present invention is to abolish the unfavorable influence of various individual plays in the devices for the tuning of string instruments and to guarantee rapid, secure and accurate tuning of the string.

This problem has been solved in that the spindle has been supported on the plate so that it may move in the direction towards the wheel and/or the wheel has been supported on the plate so that it may move in the direction towards the spindle, and in that they are subject to a directive force acting with respect to the wheel and/or the spindle respectively.

According to the present invention there have been provided, if the directive force is acting on the spindle, movable brackets on the plate for supporting the spindle and strips for guiding said brackets. According to the present invention the directive force is at least so great as or greater than the radial force of the worm gear. Preferably, the value of the directive force is not constant. The force may be produced by the pressure against the spindle exerted by adjusting adjusting screws or springs, such as compression springs, which have been provided on the plate and which, in a preferred embodiment of the present invention, are supported against adjusting screws which are provided on the plate said springs acting on the brackets in the direction towards the wheel.

Further embodiments according to the present invention are characterised in that the plate is a bending spring with bearings to support the spindle in which case the spindle bearings are flaps of the bending spring which are rolled inwards in the form of claws. The bending spring may contact the outside of the wheel by means of a partial area while pressing the same against the neck of the string instrument.

In another embodiment according to the present invention the plate may be rigid. In this case there has been provided, according to the invention, a bending spring in the form of a clip one end of which is fixed to the plate while the other end is gripping from behind the movably supported spindle. This arrangement will be favorable in that the plate may be designed in a particularly solid construction. In addition, it will also be favorable that the bending spring is pressing the gear wheel against the plate if it is placed, according to another feature of the present invention, over a wheel projection by means of a longitudinal slot and is contacting the wheel under axial pressure.

According to the present invention, therefore, the bending spring is responsible both for pressing the spindle against the gear wheel and for pressing the gear wheel against the supporting plate.

Preferably, a construction according to the present invention provides for the feature that one end of the bend-

ing spring is gripping behind a nose in the form of a hook said nose being attached to the plate at a certain distance from the same, while the spindle may movably be supported in longitudinal slots of lateral faces which have been fixed to the plate at an angle.

Further features, details and advantages of the present invention may be seen from the following description of some preferred examples of constructions according to the present invention as well as from the accompanying drawing in which:

FIG. 1 is a lateral view of an example of a construction according to the present invention;

FIG. 2 is a bottom view;

FIG. 3 is a bottom view of a second embodiment according to the present invention;

FIG. 4 is a lateral view of a third example the section being drawn along the line IV—IV in FIG. 5;

FIG. 5 is a bottom view of this embodiment;

FIG. 6 is a fourth embodiment showing a lateral view;

FIG. 7 is another example of a construction according to the present invention showing a lateral view in which the neck of the instrument has been omitted; and

FIG. 8 is a bottom view of FIG. 7.

In FIGS. 1 and 2 the plate 2 has been fixed by means of the two screws 3 and 3' to the neck 1 of the string instrument, for instance, of a guitar. The worm or wheel 4 and the spindle 5 of the worm gear are supported on said plate 2. The wheel 4 is held by means of the shaft 6 which is contacting the plate 2 from above by means of the step holder 7, and by means of the screw 8. The shaft 6 is provided with a hole 9 at its upper end to receive the string 10. The shaft ends of the spindle 5 are supported in the two brackets or bearings 11 and 11' on either side of the worm part which brackets are movable on the plate. Guidance of said brackets in the lateral directions is effected by the angular flaps 12 and 12' on either side at the plate edge. Two compression springs 13 and 13' are acting upon the brackets 11 and 11' the other ends of said springs being supported against the adjusting screws 14 and 14'. Said adjusting screws are adjustable in a flange 15 of the plate 2. The spindle 4 is activated by means of the turning handle 16.

FIG. 3 is an example of a construction according to the present invention in which the directive force acting on the spindle 5 is produced by a tension spring 19. As is the case in FIGS. 1 and 2, the wheel 4 is supported on a plate 25. The spindle 5 is supported in the branches 17 and 17' of the support 18 which is like a bow and is subject to the effect of the tension spring 19 the eyes of which are fixed to the support at 20 on one side and to the plate 25 at 21 on the other side, in the presence of prestress.

In FIGS. 4 and 5 the plate is a bending on leaf spring 26 and has for this end been provided on one end with two claw like supports 22 and 22'' to receive the spindle ends 23 and 23'.

FIG. 6 also shows a device with a plate which is a bending spring 27 which has, however, been bent towards the outside and the claws 28 and 28' of which are gripping the spindle ends 23 and 23' from the bottomside. The bending spring 27 presses the wheel 4 against the socket 24 inserted into the neck 1 of the guitar.

In the embodiments of the present invention as shown in FIGS. 7 and 8 the wheel 4 is supported by the plate 29 by means of the shaft 6 and the spindle 5 is journaled in two lateral flanges 30 and 30' of the plate by means of its ends 23 and 23', said lateral flanges being fixed to the plate 29 at an angle, preferably by bending so that they are one piece together with said plate.

The shaft 6 is lengthwise retained with reference to the plate 29 by means of its step or shoulder 33 which support is effected by a leaf spring 35 which is bent to act as a clip and which, by means of its elongate slot 32, engages the pin projection 31 of the wheel 4.

Said spring 35 is gripping from behind a nose 37 by

means of its hooked end 36, said nose being located at the flange 34 of the plate 29.

By means of its other end 38 which is like a claw and rolled inwards, the spring 35 grips the spindle 5, preferably at the threaded portion of the same. Consequently, the spring 35 exerts a directive force on the spindle 5 in the direction towards the wheel 4.

As stated before, the shaft ends 23 and 23' of the spindle 5 are supported in the lateral flanges 30 and 30' of the plate 29. To this end, said lateral flanges have each a longitudinal slot 39 and 39' respectively in which the spindle 5 may move in the direction towards the wheel 4 and back.

It is advantageous to make the wheel 4 and the shaft 6, as is the case in the embodiment shown, as an integral part.

As may be seen from the drawing, the embodiment shown is especially favorable with respect to its production and its assembly is very simple.

20 Due to pressing of the spindle against the wheel by means of a directive force a rapid play free engagement between the spindle and the wheel is obtained according to the present invention enabling, therefore, quick and accurate tuning of the instrument strings. As compared to the devices already known the device for the tuning of the strings of musical instruments has further important favorable features. For the first a distance between axles which is too small, which with the devices already known providing for rigid spindle bearing results 25 in blacking, is compensated by the spring support of the spindle; secondly, from the same reason, automatic adjustment of the spindle in the case of wear of the wheel and/or the spindle is effected.

30 As has already been mentioned, the idea of the present invention may also be realised in that the directive force is acting against the wheel in the direction towards the spindle in which case, for instance, the shaft 6 may at least be movable in the plate 2. If so desired, the idea of the present invention may also be realised in that a directive force is acting on the spindle against the wheel and a directive force on the wheel against the spindle.

I claim:

35 1. A device for tuning strings of a stringed musical instrument having a neck portion, said device comprising in combination:

a support plate attachable to the neck portion of the instrument;

a shaft rotatably supported by said plate protruding at both ends therefrom, one protruding end of the shaft being arranged to secure thereto one end of a string to be tuned;

a worm gear means including a worm wheel and a co-acting spindle, said worm wheel being secured to the other protruding end of the shaft for rotating the shaft by rotation of the worm wheel;

mounting means on the support plate rotatably supporting the spindle and displaceable parallel to its axis and normal to the rotational axis of the worm wheel; and

bias means included in said mounting means and directionally biasing said spindle into continuous rotation transmitting engagement with said worm wheel, said bias means including a springy portion on said mounting means, said springy portion defining a bearing rotatably supporting the spindle and biasing the same into said continuous play-free engagement with the worm wheel,

whereby rotation of said spindle in either direction and corresponding rotation of the shaft causes a corresponding play-free tightening or slackening of a string secured to the shaft.

2. The device according to claim 1 wherein the bias means included in said mounting means comprises a leaf spring connected on one end to said support plate, the free end of the leaf spring biasing the spindle into said

continuous play-free engagement with the worm wheel.
 3. The device according to claim 2 wherein said one end of the leaf spring terminates in a hook portion releasably engaged with a nose portion on the support plate.

4. The device according to claim 2 wherein said support plate has thereon a pair of parallel flanges extending normal to the rotational axis of the worm wheel, each of said flanges including a lengthwise elongate slot, said spindle being rotatably held in said slots displaceable therein parallel to its axis, said free end of the leaf spring biasing the spindle into said rotation transmitting play-free engagement with the worm wheel.

5. The device according to claim 2 wherein said leaf spring includes an elongate opening engaged by a pro-

trusion of the worm wheel, said opening permitting a limited movement of the leaf spring relative to the worm wheel.

6. The device according to claim 2 wherein said shaft for securing the string thereto and said worm wheel are made of one piece.
